Primary Examiner—Susan J. Lucas*Assistant Examiner*—Jennifer A. Regester*Attorney, Agent, or Firm*—Nils H. Ljungman and Associates**[57] CLAIM**

The ornamental design for an electronic information display device, as shown and described.

DESCRIPTION

FIG. 1 is a perspective view of a first embodiment of the electronic information display device showing the front side of the display device with the front cover in place;

FIG. 2 is a perspective view of the first embodiment of the display device showing the front side of the display device with the front cover partially opened;

FIG. 3 is a perspective view of the first embodiment of the display device showing the back side of the display device with the front and rear covers in place;

FIG. 4 is a perspective view of the first embodiment of the display device showing the back side of the display device with the front cover in place and the rear cover partially opened;

FIG. 5 is a perspective view of a second embodiment of the display device showing the front side of the display device with the front cover in place;

FIG. 6 is a perspective view of the second embodiment of the display device showing the front side of the display device with the front cover partially opened;

FIG. 7 is a perspective view of the second embodiment of the display device showing the back side of the display device with the front and rear covers in place;

FIG. 8 is a perspective view of the second embodiment of the display device showing the back side of the display device with the front cover in place and the rear cover partially opened;

FIG. 9 is a perspective view of a third embodiment of the display device showing the front side of the display device with the front cover in place;

FIG. 10 is a perspective view of the third embodiment of the display device showing the front side of the display device with the front cover partially opened;

FIG. 11 is a perspective view of the third embodiment of the display device showing the back side of the display device with the front and rear covers in place; and,

FIG. 12 is a perspective view of the third embodiment of the display device showing the back side of the display device with the front cover in place and the rear cover partially opened.

UNITED STATES PATENT AND TRADEMARK OFFICE
CERTIFICATE OF CORRECTION

PATENT NO. : D385,580

DATED : October 28, 1997

INVENTOR(S) : Norbert HETZER

It is certified that error appears in the above-identified patent and that said Letters Patent is hereby corrected as shown below:

On the title page, item [56], under the FOREIGN PATENT DOCUMENTS section, first reference, after '12/1991', delete "Australia" and insert --Austria--.

Signed and Sealed this
Fourteenth Day of April, 1998
